UNITED STATES PATENT OFFICE.

EDWARD W. MULL, OF COLUMBUS, OHIO.

CHOCOLATE-COOLING MECHANISM.

SPECIFICATION forming part of Letters Patent No. 752,636, dated February 16, 1904.

Application filed May 12, 1902. Serial No. 106,880. (No model.)

To all whom it may concern:

Be it known that I, EDWARD W. MULL, a citizen of the United States, residing at Columbus, in the county of Franklin and State of Ohio, have invented a certain new and useful Improvement in Chocolate-Cooling Mechanism, of which the following is a specification.

My invention relates to chocolate-candy coolers of that class which are adapted for use in cooling and hardening chocolate candies; and the objects of my invention are to provide a cooling mechanism of this class of improved construction and arrangement of parts; to so construct my improved cooling mechanism as to insure a comparatively strong current of cold air being directed or discharged at the proper points; to provide in conjunction therewith an improved chocolate-containing table or receptacle; to provide improved means for conveying candy-containing trays, and to produce other improvements the details of construction of which will be more fully pointed out hereinafter. These objects I accomplish in the manner illustrated in the accompanying drawings, in which—

Figure 1 is a side elevation of my improved cooling device. Fig. 2 is a central longitudinal section of the same enlarged from that shown in Fig. 1. Fig. 3 is a sectional view on line xx of Fig. 2. Fig. 4 is a plan view of the inner end portion of the elongated cooling and air-conducting chamber with the top removed. Fig. 5 is a sectional view through a portion of one of the upper flues of the air-conduit or cooling-chamber taken on line tt of Fig. 4 and enlarged therefrom. Fig. 6 is a plan view of a portion of the work and chocolate-containing table, and Fig. 7 is a transverse section on line zz of Fig. 1.

Similar numerals refer to similar parts throughout the several views.

In carrying out the present invention it is designed to direct currents of cold air against the candies to cool the chocolate thereon, and therefore I employ any suitable form of air-cooling or refrigerating device—as, for instance, a box or casing, indicated at 1, having a pipe-coil 5 therein, which is designed to be embedded within ice or other suitable cooling medium, with one end piercing the adjacent

wall of the box and connected to a suitable power-driven fan 34, while its opposite end also pierces one wall of the box for communication with an air-conducting device, which will be hereinafter described. Connecting with the rear side of the box 1 is a comparatively long horizontally-arranged housing or casing 8, which is formed in its upper portion and on opposite sides with flues 9, which extend throughout the length of said casing or housing. Between these flues 9 and connecting therewith through the medium of air-openings 10 is formed a central upper flue 11, the bottom plate of which is formed with openings 12, which lead into the main passage 13 of said casing. The casing 8 is provided on its sides at intervals with doorways leading into the main air-passage 13, which are adapted to be closed by suitable hinged doors 14. The casing or housing 8 is supported by means of suitable legs or supports 15, which bear upon the upper side of a horizontal work-table 16, this work-table having under side supports 17 and having its upper side recessed to provide a longitudinal chocolate-receptacle 18, the latter having laterally-extending branch recesses 19. (See Fig. 6.) Leading downward from the oppositely-located side flues 9 of the casing 8 are comparatively small air-pipes 20, these air-pipes being arranged at desirable intervals and extending to within close proximity of the work-table 16. As indicated in the drawings, these air-pipes are provided with angular terminations.

In order to control the passage of air from the side flues 9 to the central flue 11, I provide on the outer sides of said central flue horizontally-arranged damper-plates 21, these damper-plates being provided at intervals with openings 22. (See Fig. 5.) In order to move these damper-plates to positions which will insure the openings 22 thereof registering with the openings 10 or to positions which will insure the closing of said openings 10, I provide each of the damper-plates with an outwardly-extending operating-rod 23, the inner end of which is provided with a short crank-arm 24, which is pivotally connected with said damper-plate.

Journalized beneath the rear and forward

ends of the housing or casing 1 are transverse shafts 25 and 26, over which runs horizontally an endless carrier apron or belt 27. The shaft 25 is provided with a belt-wheel 28, which 5 through a belt 29 is connected with a wheel 30 on a counter-shaft 31, this shaft being connected, through a belt 32, with a main operating-shaft 33, which is rotated from any suitable source of power. That portion of the 10 pipe 5 which is in front of the box 1 is connected with a suitably-driven power-operated fan 34. Beneath the work-table 16 I preferably employ one or more steam-pipes 35, the heat from which is designed to keep in desired melted condition the chocolate contained 15 within the receptacle 18 of said table.

In utilizing my invention the air which is blown by the fan 34 through the pipe 5 becomes thoroughly cooled during its passage 20 through the various arms of said pipe which are contained within the box, and from said pipe the air thus cooled passes into the flues 9 of the casing 8, this air-current from the pipe being deflected into both of said flues by 25 causing the pipe 5 to discharge against the converging end walls of the central flue 11, these converging walls being indicated more clearly in Fig. 4 of the drawings. The air which is thus directed into the flues 9 may escape 30 therefrom through the openings 10 into the central flue 11, the amount of air which is thus directed to said central flue being controlled by the movement of the damper-plates 21. From the central flue the air may escape 35 through the bottom openings 12 into the main passage 13. It will also be understood that a portion of the air which is forced, as described, into the parallel flues 9 may pass outward and downward through the pipes 20. 40 In utilizing my improved cooling mechanism for the purpose of cooling chocolate-dipped candies the candies are covered in the usual manner with the liquid chocolate contained in the receptacle 18 of the work-table and when 45 thus treated are arranged one after the other upon a suitable tray, which rests upon the table 16 in such position that the cooled air escaping from an adjacent pipe 20 will come into contact with the candy and serve to cool and 50 harden the chocolate thereon. A tray being thus filled with candies, one of the doors 14 may be opened and the tray inserted within the main passage 13 of the casing 8, where it 55 may rest until the candies thereon are thoroughly cooled and the chocolate sufficiently hardened. From the interior of the casing 8 the chocolate-containing trays are removed and placed upon the continuous belt or apron 27 and carried thereby to a suitable receiving-table 36, arranged at the end of said traveling belt. It is obvious that when the air-discharging pipes 20 are not in use the open ends thereof may be corked or otherwise closed.

From the construction which I have herein 65 shown and described it will be seen that re-

liable and effective means are provided for discharging air at various points over the work-table, thereby permitting the chocolate-dipped candies being cooled and hardened as fast as the same are dipped.

70

Having now fully described my invention, what I claim, and desire to secure by Letters Patent, is—

1. In an apparatus of the character described, the combination with a refrigerating 75 device, of a cold-air-conducting casing leading therefrom and provided with doorways having doors, and air-discharge tubes leading at intervals from the casing.

2. In an apparatus of the character described, the combination with a refrigerating device, of a cold-air-conducting casing leading therefrom and provided with separated flues 80 communicating with the main passage of the casing, said casing having doorways and doors 85 therefor, and also provided with air-discharge tubes leading at intervals from the flues.

3. In an apparatus of the character described, the combination with a refrigerating device, of a cold-air-conducting casing leading 90 therefrom and provided with doorways having doors, a work-table disposed below the casing, and air-discharge tubes leading from the casing to the top of the table.

4. In an apparatus of the character described, the combination with a work-table, of a refrigerating device, and a cold-air conduit leading therefrom, disposed above the table and provided with doorways having doors to receive the work from the table.

95

5. In an apparatus of the character described, the combination with a work-table, of a refrigerating device, a cold-air conduit leading therefrom, disposed above the table and provided with doorways having doors, and a 105 conveyer working longitudinally in the space between the work-table and the conduit.

6. In an apparatus of the character described, the combination with a work-table, of a refrigerating device, a cold-air conduit leading 110 therefrom, disposed above the table and provided with doorways having doors, air-discharge pipes leading from the conduit to the top of the table, and a conveyer working longitudinally in the space between the table 115 and the conduit.

7. In an apparatus of the character described, the combination with a work-table, of a refrigerating device, a cold-air conduit leading 120 therefrom, disposed above the table and provided in opposite sides with doorways having doors, air-discharge pipes leading from opposite sides of the conduit to the top of the table, and a conveyer working in the space between the table and the conduit and between the pipes.

8. In an apparatus of the character described, the combination of a work-table, a work-receiving table leading from one end of the first-mentioned table, a refrigerating de- 125

130

vice at the opposite end of the work-table, a cold-air conduit leading from the refrigerating device, disposed above the work-table and provided with doorways having doors, and a conveyer working in the space between the work-table and conduit and leading from the refrigerating device to the work-receiving table.

9. In an apparatus of the character described, the combination of a work-table, a work-receiving table at one end of the first-mentioned table, a refrigerating device at the opposite end of the work-table, a cold-air conduit leading from the refrigerating device and disposed above the work-table, air-discharge pipes leading from the conduit to the top of the work-table, and a conveyer disposed between the work-table and the conduit and leading from the refrigerating device to the work-receiving table.

10. In an apparatus of the character described, the combination of a work-table, a work-receiving table at one end of the first-mentioned table, a refrigerating device at the opposite end of the work-table, a cold-air conduit leading from the refrigerating device, disposed longitudinally above the work-table and provided with doorways having doors, air-discharge pipes leading from the conduit to the top of the work-table, and a conveyer located between the work-table and the conduit and leading from the refrigerating device to the work-receiving table.

11. In an apparatus of the character described, the combination of a work-table having a liquid-receptacle, a heater for the receptacle, a cold-air conduit disposed above the table, and air-discharge pipes leading from the conduit to the top of the table.

12. In an apparatus of the character described, the combination of a work-table having an intermediate longitudinal receptacle, a heating-pipe for the receptacle, a cold-air conduit disposed above the table, and air-discharge pipes leading from the conduit to the top of the table.

13. In an apparatus of the character described, a work-table having an intermediate longitudinal receptacle provided with lateral extensions, and a conveyer working longitudinally over the receptacle, the lateral extensions of the receptacle being projected beyond the conveyer to give access to said extensions.

14. In an apparatus of the character described, the combination of a work-table hav-

ing an intermediate longitudinal receptacle 55 provided at opposite sides with transverse extensions, a cold-air conduit disposed above the table, air-discharge pipes leading from opposite sides of the conduit to the top of the table, and a conveyer disposed between the table and 60 the conduit and also between the pipes and over the receptacle of the table, the extensions of the receptacle being projected at opposite sides of the conveyer.

15. In an apparatus of the character described, a cold-air conduit divided into a lower main passage, an upper intermediate flue having a perforate bottom, and upper side flues at opposite sides of the intermediate flue, the side flues and the intermediate flue having 70 damper-controlled communications, the main passage being provided with doorways having doors, and air-discharge pipes leading from the side flues.

16. In an apparatus of the character described, a cold-air conduit having an intermediate horizontal partition forming a lower main passage, which is provided with doorways and doors, a pair of vertical longitudinal partitions dividing the upper portion of 80 the conduit into an intermediate flue and opposite side flues, all of the partitions having perforations to establish communication between the several parts of the conduit, slideable damper-plates for the perforations of the 85 vertical partitions, rotatable controlling-rods piercing opposite sides of the conduit and having cranks pivotally connected to the respective slides, handles upon the outer ends of the rods, the air-discharge pipes leading from 90 the side flues.

17. In an apparatus of the character described, the combination with a work-table, of a cold-air conduit located above the table and provided with a lower main passage and 95 upper intermediate and side flues, the bottom of the intermediate flue being provided with apertures, the side flues having damper-controlled communications with the intermediate flue, the main passage having doorways and 100 doors therefor, air-discharge pipes leading from the side flues to the table, and a refrigerating device in communication with the side flues only.

EDWARD W. MULL.
